UNITED STATES PATENT OFFICE

169,669

HANDBAG

William H. Hardy, River Edge, N. J.

Application January 7, 1953, Serial No. 23,057

Term of patent 14 years

(Cl. D87—3)

To all whom it may concern:

Be it known that I, William H. Hardy, a citizen of the United States, residing in River Edge, in the county of Bergen and State of New Jersey, have invented a new, original, and ornamental Design for a Handbag, of which the following is a specification, reference being had to the accompanying drawing, forming part thereof.

Fig. 1 is a front perspective view of a handbag, showing my new design;

Fig. 2 is a top view thereof;

Fig. 3 is a back view thereof, and

Fig. 4 is a top view thereof in open position.

I claim:

The ornamental design for a handbag, substantially as shown.

WILLIAM H. HARDY.
